UNITED STATES PATENT OFFICE

136,394

DESIGN FOR A SET OF POKER CHIPS

James F. Cooper, Darby, Mont.

Application December 29, 1942, Serial No. 109,160

Term of patent 14 years

To all whom it may concern:

Be it known that I, James F. Cooper, a citizen of the United States, residing at Darby, in the county of Ravalli and State of Montana, have invented a new, original, and ornamental Design for a Set of Poker Chips, of which the following is a specification; reference being had to the accompanying drawing, forming a part thereof.

Figures 1 to 5, inclusive, are face views of one of the twenty chips of each suit of a set of poker chips showing my new design, and

Figure 6 is an edge view of any one of the chips.

Both sides of each of the chips are the same.
The drawing is shaded to represent color.

I claim:

The ornamental design for a set of poker chips, as shown and described.

JAMES F. COOPER.
